H. Vail,
Fence Post,
Patented Feb. 1, 1833.

Feb 1 1833

Henry Hall
Post Master

Dear Sir, I enclose a copy of a letter I wrote and making part of the
same, concerning a complaint in the name of the late Henry Hall, to the
Post Master of Boston, of his appointment in Boston. I will

In all which these presents shall come.

I do however that I having been of the town of Concordville in the
County of Concord & State of Mass. have made a most useful ex-
periment in fence posts & their parts placed in situations where the force
of post will be to resist the following is a full & exact description
of fence posts and ornaments I have. That portion of the post placed
in the ground is liable to many parts to be made of iron. This iron is to be cast or
made much in the shape of an ordinary spade, & if the blade should be
straight, & the top part of the post should be
about one and one half inches long to support an ordinary fence post
the top should be about one and a half inches in diameter where it
joins the blade & about three quarters of an inch at the upper end this in-
serted into a round hole or a with a common taper cut to the lower
end of the post. The blade or transom should be about three inches wide
at which end a little broader at the middle where the top is joined
to it. The other end of the post is also to be about three inches wide
at which end a little broader at the middle where the top is joined
to it. The height of fence posts you may choose according to the height of
the field or the land on which it is to be applied. To go to a fence post stand
up about 3 feet from the fence in one direction, a wing or wings
about 12 feet from the fence, & the other blade standing out forming right
angle with the end of the other blade.

Henry Hall
